UNITED STATES PATENT OFFICE.

JOHN P. REILY, OF ST. LOUIS, MISSOURI.

BOOT OR SHOE HEEL.

1,275,748.

Specification of Letters Patent. Patented Aug. 13, 1918.

Application filed March 23, 1918. Serial No. 224,200.

To all whom it may concern:

Be it known that I, JOHN P. REILY, a citizen of the United States, residing at St. Louis, Missouri, have invented a certain new and useful Improvement in Boot or Shoe Heels, of which the following is a full, clear, and exact description, such as will enable others skilled in the art to which it appertains to make and use the same, reference being had to the accompanying drawings, forming part of this specification.

My invention relates generally to footwear and more particularly to a heel for boots and shoes, the principal object of my invention being to provide a heel which is especially applicable for ladies' shoes and to arrange on the lower end of said heel a lift or section of rubber or analogous yielding material, and which lift is readily removable in order that it may be taken off when it becomes worn or unfit for service and replaced by a new lift.

It is the present practice to a large extent to apply wooden heels to ladies' shoes, the external surfaces of said heels being finished with enamel or the like, and it is one of the objects of my invention to provide means preferably in the form of a bolt which extends vertically through the central portion of the heel, thereby materially strengthening the heel body and reducing to a minimum the tendency of the heel to break or split transversely at a point between its top and bottom.

A still further object of my invention is to provide a heel having a readily removable lift in which is embedded a series of wear resisting members, preferably metal and which latter, in addition to resisting wear, tend to prevent slipping when the under surface of the lift comes in contact with a smooth or slippery surface.

With the foregoing and other objects in view, my invention consists in certain novel features of construction and arrangement of parts, hereinafter more fully described and claimed, and illustrated in the accompanying drawings, in which—

Figure 1 is a vertical section taken through the center of a heel of my improved construction.

Fig. 2 is a perspective view of the removable lift forming a part of my invention.

Fig. 3 is a view looking against the under side of the lift.

Fig. 4 is a view looking against the under-

side of the lift retaining member which is applied to the underside of the heel body.

Fig. 5 is a view looking against the underside of a modified form of the lift.

Fig. 6 is a perspective view of a modified form of the wear resisting member which I use in the removable lift forming a part of my invention.

Referring by numerals to the accompanying drawings which illustrate a practical embodiment of my invention, 10 designates the body of the heel, the same being preferably formed of wood and provided at its upper end with a seat 11 which is adapted to receive the rear portion of the body of the shoe. This heel is finished in any desired fashion, and is secured to the body of the shoe in a manner well known to the trade.

Secured to the underside of the body of the heel 10, preferably by means of screws 12, is a plate 13, preferably of metal, the shape of which corresponds to the shape of the lower edge of said heel body. Depending from the edge of this plate 13 is a flange 14 and projecting inward from the lower edge of this flange 14 is a short horizontally disposed flange 15.

Passing through the central portion of the heel body 10 is a bolt or rod 16 which serves to reinforce the central portion of the heel body and prevent it from breaking or splitting horizontally at a point between its top and bottom. The upper end of this bolt is pivotally connected to an ear or short extension on the underside of a disk 16^a which latter is positioned on top of the heel portion of the sole A of the shoe and thus said heel is firmly secured to the body of the shoe. By pivotally connecting the disk 16^a to the upper end of the bolt, said disk readily adjusts itself to the angularity of the shoe sole. The threaded lower end of bolt 16 projects through the plate 13 and receives a nut 16^b which, when tightened, firmly holds the bolt in position in the heel.

The lift contemplated by my invention comprises a body 17 of resilient flexible material such as rubber or composition which includes rubber, and formed integral with the top of this body is a plug 18 having a beveled edge 19 and the latter being spaced apart from the top face of the body of the lift. This plug 18 is of such size as to fit snugly within the space between plate 13 and flange 15 and when properly applied for

use, the beveled edge 19 of said plug overlies flange 15, and thus said lift is retained upon the heel body.

Formed in the top of plug 18 is a rectangular recess 17^a which receives the nut 16^b on the lower end of bolt 16, and thus said nut is prevented from turning when the lift is properly positioned on the heel.

It will be understood that in applying the lift to the heel body, sufficient pressure must be used to compress the plug 18 and particularly the beveled edge 19 thereof and force the latter into position above flange 15, and likewise when the lift becomes worn or unfit for service and it is desired to replace it with a new lift, sufficient pulling force must be applied to the lower portion of the old lift to disengage the beveled edge 19 of plug 18 from the flange 15.

Embedded in the lower portion of the body 17 of the lift is a series of wear resisting members 20, preferably metal and in the form of rings. It will be understood that these wear resisting members are effective in preventing rapid wear of the lower portion of the lift and likewise said members materially assist in preventing slipping of the lift when the latter encounters a smooth or slippery surface.

In Fig. 6, I have shown a modified form of the wear resisting members, the same being constructed in short tubular sections and the wall of each section being provided with a series of apertures *a*. These members are embedded in the lift when the same is molded, and consequently, portions of the body of said lift will occupy the apertures *a*, thereby firmly anchoring the wear resisting members in said lift.

In some instances it may be found desirable to dispense with the wear resisting members 20 and to roughen or corrugate the underside of the lift as illustrated in Fig. 5.

A shoe heel of my improved construction is comparatively simple, can be easily and cheaply manufactured, and by making the lifts readily removable, the cost of repairs in replacing lifts is materially reduced.

It will be readily understood that minor changes in the size, form and construction of the various parts of my improved shoe

heel may be made and substituted for those herein shown and described, without departing from the spirit of my invention, the scope of which is set forth in the appended claims.

I claim:

1. The herein described heel comprising a heel body, a plate secured to the underside of said heel body, a continuous L-shaped flange depending from the marginal edge of said plate, a lift applied to the underside of said flange, a plug integral with said lift, which plug occupies the space within said flange and overlies the horizontally disposed portion thereof, the top of which plug is flat and bears directly against the underside of the plate, and the edge of said plug being beveled so as to facilitate its entrance into the space within the flange. 70

2. A heel comprising a heel body, a plate applied to the underside of said body, a member passing through said plate and extending upwardly through the central portion of the heel body, and a disk pivotally connected to the upper end of said member and adapted to overlie the heel portion of the shoe sole to which the heel is applied. 75

3. A heel comprising a heel body, a lift removably applied to the underside of said heel body, a bolt passing vertically through the central portion of the heel body, and a disk pivotally secured to the upper end of said bolt and adapted to overlie the heel portion of the shoe sole to which the heel is applied. 80

4. A heel comprising a heel body, a plate applied to the underside of said heel body, a lift removably applied to said plate, the top of said lift being provided with a recess, a bolt passing vertically through the central portion of the heel body, a nut on the threaded lower end of said bolt, which nut is adapted to occupy the recess in the top of the lift, and a disk pivotally connected to the upper end of said bolt, which disk is adapted to overlie the heel portion of the shoe sole to which the heel is applied. 90

In testimony whereof I hereunto affix my signature this 9th day of March, 1918.

JOHN P. REILY.
